F. SOHNLE.
BRUSH HOLDER.
APPLICATION FILED JULY 19, 1920.

1,391,017.

Patented Sept. 20, 1921.

UNITED STATES PATENT OFFICE.

FRIEDRICH SOHNLE, OF NEWARK, NEW JERSEY.

BRUSH-HOLDER.

1,391,017.

Specification of Letters Patent. Patented Sept. 20, 1921.

Application filed July 19, 1920. Serial No. 397,500.

To all whom it may concern:

Be it known that I, FRIEDRICH SOHNLE, a citizen of the United States, and a resident of Newark, county of Essex, and State of 5 New Jersey, have invented certain new and useful Improvements in Brush-Holders, of which the following is a specification.

This invention relates to an improved brush holder particularly adapted for the 10 use of painters, and is of the kind that provides for the adjustment of a brush at different angles to the handle of the device.

The invention relates to the brush holding member which is constructed so that a minimum 15 number of parts are employed, and in which the brush is securely held, the holder also being adapted to hold scrapers, knives and other implements commonly used by painters and like workmen.

20 It becomes necessary, in many instances, particularly in painting jobs, to reach places inaccessible to the workman with an ordinary brush without the hanging or erection of a scaffold or sometimes the transportation 25 and use of ladders. This device gives access to such points by reaching from windows or from roofs to paint cornices, overhanging parts, gutters and like places without the necessity of time and expense of erecting 30 scaffolding or the like.

The invention is illustrated in the accompanying drawing, in which Figure 1 is a side view of the device on the end of a handle. Fig. 2 is a perspective view of the 35 device. Fig. 3 is an enlarged section showing brushes in various positions, and Fig. 4 is a central vertical section of Fig. 3.

The device is adapted to be attached to the handle 10, usually by simply screwing the 40 handle into the end of the device, the device comprising a tubular member 11 which has at one side a slot 12, which slot extends from the top edge of the device part way down, and a second slot 13 is opposite the slot 12 45 and overlaps the slot 12 but does not extend to the upper end of the member, there being provided thereby material, as at 14, to provide a stop.

Transversely arranged through one wall 50 of the member is a screw 15 which is provided with a finger-piece 16, and at its inner

end, to prevent marring of brush handles and the like, is provided with a washer or disk 17. The hole 18^a is placed in the member so as to permit easy heading of the end 55 of the screw 15 so that the washer 17 can be attached thereto.

The disposition of these parts is such as to permit a ready adjustment of the brush at sufficient different angles to provide for all 60 situations in which the brush is to be used. The brush 18 can be seated in the end of the member in extension thereof, as shown in Fig. 1, and when the screw 15 is screwed in tight the washer 17 bears against the handle 65 of the brush and holds the brush in position.

If the brush is to be inclined upward at an obtuse angle to the member, as shown at *a* 70 in Fig. 3, it is slid down through the open end of the slot 12 and through the slot 13 and held in position by the screw, as will be readily seen.

The brush can be placed horizontally, as at *b*, that is, at right angles to the member, 75 and it can also be placed at an acute angle to the member, as represented at *c*, by passing the handle first through the slots 13, the open end of the slot 14 permitting the free end of the handle to project beyond the member and 80 also providing a considerable play so that the brush can be swung to the desired angle.

When the brush is in the position shown at *a* it is used for painting cornices and the like, and similar situations can be found 85 where such arrangement of the brush is desirable.

When the brush is arranged as at *c* it can be used for painting gutters or for painting the edges of roofs by a painter standing on the roof, and particularly for painting the overhanging part of a roof structure. 90

The device is cheaply made and there are no parts to be adjusted on the device, since the device itself remains fixed, but the brush handle, due to the particular arrangement of the slots, can be arranged at sufficient desirable angles to make a practically universal adjustment of the brush possible. 95

I claim:

A brush holder comprising a tubular member having a narrow slot in one side extend-

100

ing from one end part way of the length of the member and having a long narrow slot on the side opposite the first slot, the second slot terminating short of the end of the member and extending a material distance beyond the inner end of the first slot, and a binding screw screwed through one wall of

the member and adapted to press against the handle of a brush held in the slots.

In testimony that I claim the foregoing, I have hereto set my hand, this 17th day of July, 1920.

FRIEDRICH SOHNLE.
